ATOMIZER

Alex Limbach, Carmel, N. Y.

Application February 5, 1942, Serial No. 429,625

12 Claims. (Cl. 299—88)

This invention relates to liquid-dispensing devices such as atomizers or sprayers.

An object of this invention is a simple and inexpensive liquid dispenser assembly adapted for easy attachment to a container in which insecticide or other liquid is merchandized or to a threaded member for dispensing any liquid.

It is quite customary to merchandize insecticide and the like in a metal container having an exteriorly threaded neck on which is provided a cap. The dispenser of this invention is particularly adapted to be screwed on to the threaded neck of such container after removal of the original cap and puncturing of the container seal if the container is provided with a seal.

The structure of certain forms of the dispenser is such that in order to use the dispenser, the container is inverted so that liquid feeds therewith into the dispenser by gravity and the dispenser is provided with a bulb or other suitable means for producing a stream of air which effects atomization of the liquid and discharges it in the form of an atomized spray. When not in use, the container is placed in its normal position and there is no tendency for liquid to escape from the container through the dispenser. In other embodiments of the apparatus, the structure is such that liquid is withdrawn from the container by vacuum so that the dispenser may be operated with the container in normal position and the dispenser at a higher level than the liquid in the container.

Other objects, novel features and advantages of this invention will become apparent from the following specification and accompanying drawings, wherein:

Fig. 1 is a vertical section through a dispenser embodying the invention with the dispenser being shown in non-operating position;

Fig. 2 is a section on the line 2—2 of Fig. 1;

Fig. 3 is a section on the line 3—3 of Fig. 1;

Fig. 4 is a vertical section of a second embodiment with the dispenser being shown in operating position;

Fig. 5 is a side elevation of the dispensing elements of Fig. 4;

Fig. 6 is a plan view of Fig. 5, and

Fig. 7 is a sectional view of a modification of Fig. 1.

A container 10 is provided with a neck 11 having an exterior screw thread. A cap 12 is interiorly threaded for co-operation with the threads of the neck 11 to hold the cap on the neck. In the cap 12 is provided a circular central recess 13 thereby forming an annular shoulder 14. The

cap has a tube 15 leading from the recess 13 to a hollow bulb 16 of ordinary construction or other means of providing air under pressure.

A preferably circular plate or similar planar member 17 engages the shoulder 14 and an apertured planar member or sealing washer 18 underlies the plate 17 and is engaged by the rim of the neck 11. Preferably, the member 17 is composed of plastic material while the member 18 may be composed of any suitable sealing material. An airtight seal is formed between the member 17 and the shoulder 14 preferably by cementing the member to the shoulder. The washer 18 may be attached to the plate 17 by cement or may be held against it by friction exerted through the medium of the inner end of the neck 11.

In the plate 17 are provided two aligned radial grooves 19 and 20 on opposite surfaces of the plate and the cap 12 is provided with an aperture 21 in register with the ends of the grooves 19 and 20. The groove 19 forms a passageway between the plate 17 and the shoulder 14 while the groove 20 forms a passageway between the plate 17 and washer 18.

In operating the dispenser above described, its position of use is just reverse from that shown in Fig. 1, such position of use being the same as illustrated in Fig. 4. The container 10 is then arranged at a higher level than the bulb 16 as well as at a higher level than the passageway formed by the groove 20. Compression of the bulb 16 forces air through the tube 15 into the recess 13 and through the groove 19 to the aperture 21. The flow of air through the groove 19 draws liquid from the container 10 into the groove 20 and through it into the discharge aperture 21, thereby atomizing the liquid and projecting it through the discharge opening 21 in an atomized spray. When the arrangement is not being used, it is placed in the position shown in Fig. 1 in which condition there is no tendency for liquid to flow through the passageway 20 due to the fact that the passageway is at a higher elevation than the liquid in the container.

In the modification of Figs. 4 to 6, a preferably circular metal plate or planar member 30 contacts the shoulder 14 and in a groove 31 in the shoulder is preferably provided a gasket 32 against which projects the oblique flange 33 of the plate 30 to form an air-tight seal. A radial portion of the plate 30 is offset to form a groove 34 which provides a passageway between the plate and the shoulder 14 leading to the discharge aperture 21. A second preferably circular metal

plate or planar member 35 engages the plate 30 and a radial portion thereof is offset to form a groove 36 in which is received the offset portion of the disk or plate 30. The size and length of the two offset portions are such that they provide a passageway 36a between the two plates leading to the discharge aperture 21. A ring gasket 37 is preferably interposed between the inner end of the neck 11 and the plate 35 and in said plate is provided a minute aperture 38 communicating with the passageway between the two plates 30 and 35.

In the operation of the modification of Fig. 4, the dispenser is held in the position shown in Fig. 4. Compression of the bulb 16 forces air through the tube 15 into the recess 13 and through the groove 34 to the discharge opening 21. Such flow of air draws liquid from the container through the aperture 38 and through the passageway between the two plates into the discharge opening 21, thereby atomizing the liquid and projecting it through the discharge opening in the form of atomized spray. When the dispenser is not in use, it is arranged in the position shown in Fig. 1 with the bulb 16 at a higher elevation than the container 10.

In the modification illustrated in Fig. 7, the sealing washer 18 has a smaller aperture than in the modification illustrated in Fig. 1 and in said aperture is received one end of a tube 40, the other end of which is arranged adjacent the bottom of the container 10. The upper end of the tube 40 communicates with the inner portion of the groove 20. Except for the differences just mentioned, the structure of the modification of Fig. 7 is identical with that of Fig. 1.

In the operation of the modification of Fig. 7, compression of the bulb 16 forces air through the tube 15 into the recess 13 and through the groove 19 to the aperture 21. The flow of air through the groove 19 produces a vacuum which is effective to draw liquid through the tube 40 into the groove 20 and through it into the discharge aperture 21 thereby atomizing liquid and projecting it through the discharge opening in an atomized spray.

The container is held in normal position and no inversion of it is required as is required with the dispenser of Fig. 1. The dispenser structure of Fig. 7 is a bit more expensive than that of Fig. 1 due to the added material and manufacturing operation necessary to produce it.

Although the planar member 18 of Fig. 1 has been shown as a washer, it is to be understood that it may be constructed in the form of a disk having a minute central aperture of the same type as the aperture 38 in the planar member 35 of Fig. 4. Also, in the modification of Fig. 4, the disk 35 may be replaced by a disk-like member having a central aperture comparable to the aperture in the washer 18 of Fig. 1. Likewise, the modification of Fig. 4 may be further modified by the provision of a tube similar to the tube 40 of Fig. 7, such tube leading from the bottom of the container 11 to the aperture 38 whereby the atomizer may be operated with the container in normal rather than in inverted position.

In all of the modifications, the atomizer structure is of extreme simplicity and inexpensive to manufacture due both to the small amount of material used and the simple manufacturing operation. The manufacturing operations are limited either to molding grooves in a plastic member or to bumping grooves in thin metallic members. Each of these operations can be ac-

complished with inexpensive equipment by unskilled labor and the cost of the material forming the disks is very slight.

If in the modifications of Figs. 1 and 4 the container is made of thin sheet metal, the volume of the atomized discharge may be materially increased by applying pressure to the sides of the container. Such pressure forces liquid into the discharge channel at a greater rate than it is fed thereto merely by gravity. With this simple and inexpensive structure, it is only necessary to attach the dispenser to a supply of liquid and the air stream supplied from a bulb or other suitable means will dispense any liquid in atomized or spray form.

It is of course understood that various modifications may be made in the atomizer structure above described without in any way departing from the spirit of the invention as defined in the appended claims.

I claim:

1. A liquid dispenser comprising a first imperforate planar member and a second planar member, an annular element engaging one face of said first member adjacent the periphery thereof, means clamping together said members and annular element, a first passageway leading between said annular element and said first member, a second passageway leading between said two members, each of said passageways being formed in part at least by a groove in one of said members and both of said passageways terminating at the periphery of the first member in alignment with each other, a transverse aperture in said second member communicating with the inner portion of said second passageway, means for supplying air to said first passageway, and means for supplying liquid through said aperture to said second passageway.

40 2. A liquid dispenser comprising a first imperforate thin metal planar member and a second thin metal planar member, an annular sealing element engaging one face of said first member adjacent the periphery thereof, means clamping together said members and annular element, aligned correspondingly offset groove portions in said members forming a first passageway leading between said element and said first member and a second passageway leading between said two members with both of said passageways terminating at the periphery of the first member in alignment with each other, an aperture in said second member communicating with the inner portion of said second passageway, means for supplying air to said first passageway, and means for supplying liquid through said aperture to said second passageway.

60 3. A liquid dispenser comprising a first imperforate planar member of plastic material, an annular element engaging one face of said plastic member adjacent the periphery thereof, means including a second planar member clamping together said plastic member and annular element, aligned grooves in opposite faces of said plastic member forming a first passageway leading between said element and said plastic member and a second passageway leading between said two members with both said passageways terminating at the periphery of said first member, an aperture in said second member communicating with the inner portion of said second passageway, means for supplying air to said first passageway, and means for supplying liquid through said aperture to said second passageway.

70 75 4. A liquid dispenser comprising a first imper-

forate planar member, a second planar member, an element engaging one face of said first member, means clamping together said members and element, a first passageway leading between said element and said first member, a second passageway leading between said two members, each of said passageways being formed in part at least by a groove in one of said members and both of said passageways terminating at the periphery of the first member in alinement with each other, a transverse aperture in said second member communicating with the inner portion of said second passageway, means for supplying air to said first passageway, and means for supplying liquid through said aperture to said second passageway.

5. A liquid dispenser comprising a first imperforate thin metal planar and a second thin metal planar member, a sealing element engaging one face of said first member, means clamping together said members and element, alined correspondingly offset portions in said members forming a first passageway leading between said sealing element and said first member and a second passageway leading between said two members with both of said passageways terminating at the periphery of the first member in alinement with each other, an aperture in said second member communicating with the inner portion of said second passageway, means for supplying air to said first passageway, and means for supplying liquid through said aperture to said second passageway.

6. A liquid dispenser comprising an imperforate planar member of plastic material, an element engaging one face of said plastic member, means including a second planar member for clamping together said plastic member and element, alined grooves in opposite faces of said plastic member forming a first passageway leading between said element and said plastic member and a second passageway leading between said two members with both said passageways terminating at the periphery of said first member, an aperture in said second member communicating with the inner portion of said second passageway, means for supplying air to said first passageway, and means for supplying liquid through said aperture to said second passageway.

7. In combination, a container having an interconnected neck and cap, a recess in the closed end of said cap forming an annular shoulder, a first and a second planar member in said cap with said first member engaging said annular shoulder and said second member engaging the end of the container neck, a first passageway leading between said shoulder and said first member and communicating with said recess, a second passageway leading between said two members, both of said passageways terminating at the periphery of the first member in alinement with each other, an opening in said cap in register with the ends of said passageways, an aperture in said second member communicating with the inner portion of said second passageway, means for supplying air to said recess, and means for supplying liquid through said aperture to said second passageway.

8. In combination, a container having an interconnected neck and cap, a recess in the closed end of said cap forming an annular shoulder, a first and a second planar member in said cap with said first member engaging said annular shoulder and said second member engaging the end of the container neck, a first passageway leading between said shoulder and said first member and communicating with

5 communicating with said recess, a second passageway leading between said two members, each of said passageways being formed in part at least by a groove in one of said members and both of said passageways terminating at the periphery of the first member in alinement with each other, an aperture in said second member communicating with the inner portion of said second passageway, an opening in said cap in register with the ends of said passageways, means for supplying air to said recess, and means for supplying liquid through said aperture to said second passageway.

9. In combination, a container having an interconnected neck and cap, a recess in the closed end of said cap forming an annular shoulder, a first and a second thin metal planar member in said cap with said first member having sealing relation with said annular shoulder and said second member having sealing engagement with the end of the container neck, alined corresponding offset portions in said members forming a first passageway leading between said shoulder and said first plate and communicating with said recess and a second passageway leading between said two members with both of said passageways terminating at the periphery of said first member in alinement with each other, an aperture in said second plate communicating with the inner portion of said second passageway, an opening in said cap in register with the ends of said passageways, means for supplying air to said recess, and means for supplying liquid through said aperture to said second passageway.

10. In combination, a container having an interconnected neck and cap, a recess in the closed end of said cap forming an annular shoulder, a planar member of plastic material in said cap engaging said annular shoulder, a second planar member interposed between said plastic member and the end of the container neck, alined grooves in opposite faces of said plastic member forming a first passageway leading between said shoulder and said plastic member and a second passageway leading between said two members with both said passageways terminating at the periphery of said first member, an aperture in said second member communicating with the inner end of said second passageway, an opening in said cap in register with the ends of said passageways, means for supplying air to said recess, and means for supplying liquid through said aperture to said second passageway.

11. A liquid dispenser comprising a single imperforate planar member, an annular member engaging one face of said planar member adjacent the periphery thereof, a sealing washer engaging the other face of said planar member, means holding said planar member and said washer in position engaging said annular member, a first passageway leading between said annular member and one face of said planar member, a second passageway leading between said washer and the other face of said planar member, each of said passageways being formed in part at least by a groove in one face of said planar member both of said passageways extending to the periphery of said planar member in alinement with each other, a transverse aperture in the side wall of said annular member in line with said first and second passageways, means for supplying air to said first passageway, and means for supplying liquid to said second passageway.

12. A liquid dispenser of the spray type comprising an annular member, a single imperforate planar member with one face having sealing en-

gagement with said annular member adjacent the periphery thereof, an apertured closure disk having sealing engagement with the other face of said planar member, means holding said disk and said planar member in engagement with said annular member, a first passageway of uniform cross-section leading between said annular member and one face of said planar member, a second passageway of uniform cross-section leading between said closure disk and the remaining face 10

of said planar member, each of said passageways being formed in part at least by aligned grooves in one face of said planar member and extending to the periphery thereof, a transverse aperture in the side wall of said annular member in register with said passageways, means for supplying air to one of said passageways, and means for supplying liquid to the remaining passageway.

ALEX LIMBACH.
